UNITED STATES PATENT OFFICE.

JOSEPH KALM, OF MISSOULA, MONTANA.

HORSESHOE.

No. 918,556.

Specification of Letters Patent.

Patented April 20, 1909.

Application filed December 12, 1908. Serial No. 467,208.

To all whom it may concern:

Be it known that I, JOSEPH KALM, a citizen of the United States, residing at Missoula, in the county of Missoula and State of 5 Montana, have invented a new and useful Horseshoe, of which the following is a specification.

This invention relates to horse shoes, and more particularly to the kind designed to be 10 attached to the hoof of the animal without the use of nails.

It has for one of its objects the construction of a horse shoe equipped with a novel 15 form of heel and toe plates adapted to engage the locking member.

Another object is to provide an improved form of locking strap designed to be secured to the hoof of the animal and to the shoe.

With these and other objects in view as 20 will more fully hereinafter appear the present invention consists in certain novel details of construction and arrangement of parts, hereinafter fully described, illustrated in the accompanying drawings and 25 more particularly pointed out in the appended claims, it being understood that various changes in the form, proportion, size and minor details of the device may be made without departing from the spirit or sacrificing any of the advantages of the invention. 30

In the accompanying drawings forming part of this specification:—Figure 1 is a perspective view of the shoe and locking strap. 35 Fig. 2 is detailed perspective of the front portion of a modified form of locking strap. Fig. 3 is a front elevation of a modified form of toe clip. Fig. 4 is a modified form of nail to prevent displacement of the shoe on the 40 animal's hoof, and Fig. 5 is another modification of the same.

Similar numerals of reference are employed to designate corresponding parts throughout.

45 In carrying out the invention I provide a horse shoe with a toe clip having on its outer face projections or teeth, and on the upper face of the shoe adjacent to its opposite terminals heel clips are formed each of which is 50 provided on its inner face with a lug having a suitable channel or groove formed therein provided with teeth. With this construction a locking strap is provided which is designed to embrace the hoof of the animal, having 55 inwardly turned teeth on its lower edge designed to enter the hoof, and provided at its

terminals with teeth to engage the teeth of the heel clips. The locking strap is further provided at its central portion with spring arms which are designed to be forced under 60 the teeth of the toe clip whereby the shoe is firmly secured in place.

By referring now to Fig. 1 it will be seen that the shoe 1, is provided on its lower face with the usual toe and heel calks 2 and 3, and on its upper face, and adjacent the outer edge and extending substantially throughout the entire length of each limb are upturned prongs 4. These members are upstruck as clearly shown, and their function 70 is to enter the lower face of the hoof, similarly to the ordinary nail, so as to prevent lateral and longitudinal displacement of the shoe while on the hoof. The form of toe clip employed consists of two vertical bars 75 5 and 6, formed integral or otherwise, and secured to the upper face and at the outer edge of the shoe. These bars are disposed on either side of the center of the shoe and are slightly curved or inclined to the rear 80 to conform to the incline of the animal's hoof. Adjacent to the upper end of each bar and on the outer face is formed a forwardly projecting lug 7 constituting a tooth, the function of which will appear later. 85 The vertical clips or heel plates 8 and 9 are disposed on the upper face of the shoe and at the opposite ends thereof and have their outer faces coincident with the outer face of the shoe and their rear ends inclined forwardly from the rear upper edges of the terminals of the shoe. Each heel plate is provided on its inner face and adjacent its upper end with a thickened portion constituting lugs 10 and 11. These keepers or lugs 90 are suitably recessed or channeled on their lower end, throughout their entire length, and the floor of each channel is suitably notched so as to form teeth 12. The locking strap 13 is preferably formed of a single 95 piece of resilient metal of the approximate shape and size of the shoe 1, and on its upper edge and at either end a row of teeth 14 is formed, corresponding in number and size to the teeth 12 of the heel plates. The 100 strap is at its middle longitudinally recessed as shown at 15 for a portion approximately equal to one-third its length, the opposite ends of the recess being equidistant from the center of the strap. The portion 105 constituting the upper wall of the recess is divided at its center so as to form spring 110

arms 16 and 17. These arms are sprung inwardly and are designed to engage the teeth of the toe plate as will appear later.

In the use of the device thus far described, 5 it is designed first to apply the shoe to the hoof of the animal in the ordinary manner, and after the same has been accurately adjusted, the foot is lowered and the pressure on the prongs 4, due to the weight of 10 the animal, will ordinarily be sufficient to force the prongs into the hoof. The locking strap is next applied by inserting its opposite terminals into the channeled lugs, until the teeth 14 engage the teeth 12, during 15 this operation it is designed that the portion constituting the lower half 18 at the central or front end of the strap, shall be directly in front of the teeth 7 of the toe plate, and the spring arms 16 and 17 above 20 said teeth, so that when the teeth 12 and 14 are in engagement, a suitable clamping tool may be employed to force the body of the strap downwardly. This downward movement of the strap will cause the spring arms 25 16 and 17, when riding over the upper ends of the teeth 7, to move outwardly, and this they will continue to do until moved downward sufficiently to pass the teeth when, owing to their inward curving they will 30 spring beneath the teeth, thus completing the fastening of the shoe.

It will be observed that opposite portions 35 19 of the locking strap lying forwardly or inwardly of the teeth 14 are curved sinuously for a distance approximately equal to the length of each row of teeth, and these sinuously curved portions are, throughout their middles, provided with similarly shaped openings or recesses 20. The function 40 of this construction is to lessen the strain on the teeth 12 and 14, by permitting a longitudinal yielding of the strap when forcing the latter over the toe clip. In order further to secure the locking strap 45 against displacement, its lower edge is suitably notched so as to form teeth 21. These teeth are flexed slightly inward so that when the strap is forced downward over the toe clip they will fasten in the hoof of the animal. 50

Figs. 2 and 3 show a modified form of toe clip and locking strap. The posts 22 and 23 of the toe clip (Fig. 3) are identical to those shown in Fig. 1 with the exception 55 that each post is provided with a series of downwardly projecting teeth or lugs 24 arranged in a vertical plane on its outer face. The form of locking strap employed in connection with this toe clip is similar to that 60 already described with the exception that the spring arms 25 and 26 are provided with two or more longitudinal recesses 27, the metal at the upper side of each of these recesses is inclined slightly outward, and the 65 lower edge of the strap beneath the lower

recesses is similarly inclined, and thus it will be seen that openings are provided for the reception of the downwardly projecting teeth or lugs 24 of the toe plate.

The modified forms of fasteners illustrated in Figs. 4 and 5 are designed for use with extremely hard hoofs such as might cause the upstruck fasteners 4 to bend. In the application of the form illustrated in Fig. 4, suitable openings are formed in the 70 shoe. The fastener 28 which is substantially wedge shape, is provided on its opposite sides with barbs or serrations 29, and is longitudinally divided for a portion of its length as shown at 30, so that when the shoe 75 has been adjusted to the animal's hoof the fastener is driven in, in any well known manner. A suitable tool is next forced into the opening 30 causing the sides to spread and the serrations or barbs 29 to engage the 80 walls of the openings.

Fig. 5 shows a section of horse shoe provided with an opening similar to that shown in Fig. 4. The form of fastener employed therein consists of a wedge shaped member 90 31, of a size to fit snugly within the opening and having lateral projections or lugs 32 disposed at substantially its horizontal center. In the application of this form, the fastener is inserted in the opening before 95 applying the shoe to the hoof, and the lugs 32, resting on the upper face of the shoe, prevent the fastener from falling through the opening. A longitudinal opening 33 is formed in the lower portion which permits 100 it to be spread so as to bind tightly against the walls of the opening. It is to be understood that these fasteners are not intended for any other purpose than to prevent sliding of the shoe on the hoof. 105

What is claimed is:—

1. The combination with a horse shoe having a toe clip provided with teeth on its outer face and heel clips having keepers on their opposed inner faces, of a fastening 110 strap terminally provided with means to engage the keepers and intermediately provided with spring arms to engage the teeth of the toe clip.

2. The combination with a horse shoe having a toe clip provided with teeth on its outer face, and heel clips having keepers on their opposed inner faces; of a fastening 120 strap having its terminals and intermediate portion provided with means to engage the heel and toe clips and its lower edge provided with teeth to engage the hoof of the animal.

3. The combination with a horse shoe having a toe clip provided with teeth on its 125 outer face, and heel clips having keepers on their opposed inner faces; of a fastening strap, the terminals of which are arranged to engage the heel clips and having inwardly turned teeth on its lower edge to engage the 130

hoof of the animal, and intermediately provided with spring arms disposed above the teeth to engage the teeth of the toe clip.

4. A nailless horse shoe provided with a toe clip having teeth on its outer face and heel clips having keepers on their opposed inner faces provided with serrations, in combination with a fastening strap having its terminals arranged to engage the serrations and intermediately provided with spring arms to engage the teeth of the toe clip.

5. A nailless horse shoe provided with a toe clip having teeth on its outer face and

heel clips having keepers on their opposed inner faces provided with serrations; in combination with a fastening strap terminally provided with serrations to engage with those of the keepers, and intermediately provided with inwardly curved spring arms to engage the teeth of the toe clip.

In testimony that I claim the foregoing as my own, I have hereto affixed my signature in the presence of two witnesses.

JOSEPH KALM.
